UNITED STATES PATENT OFFICE.

WILLIAM BALDWIN VANSIZE, OF NEW YORK, N. Y.

AUTOMATIC TELEPHONE-EXCHANGE.

SPECIFICATION forming part of Letters Patent No. 744,946, dated November 24, 1903.

Application filed April 22, 1903. Serial No. 153,829. (No model.)

To all whom it may concern:

Be it known that I, WILLIAM BALDWIN VANSIZE, a citizen of the United States, residing in the borough of Brooklyn, in the city of New York, in the county of Kings and State of New York, have made certain new and useful Improvements in Automatic Telephone-Exchanges, of which the following is a specification.

10 This invention relates to apparatus for automatically connecting two subscribers' telephone-circuits into a single circuit at a central point or station, subsequently disconnecting said circuits and restoring normal conditions.

15 The object of this invention is to minimize the amount of machinery and apparatus employed, to simplify its construction, to reduce its expense and its liability to disarrangement, and to obviate the necessity for the use of anything but the most common and ordinary intelligence on the part of the calling subscriber.

20 The specific form of apparatus which I have employed to illustrate my invention and which is the best form now known to me consists of an automatic transmitter at the substation controlled by a section of perforated tape. Each substation has such a transmitter and a section of tape for each station to be called for. Each section of tape bears an arbitrary designation of the calling-station and the station called for. At the main station each substation-circuit includes a flexible

25 cord and plug-terminal. There is also a take-up device, and each plug-terminal rests at the end of a pivoted arm. The entire series of arms are arranged in the circumference of a circle. They hang vertically and when moved to a horizontal position present the plug-terminals at one and the same common point. There is a portable shell or connecting device, with four electrically-united springs arranged in two pairs to

30 receive and hold the plug-terminals. In the operation of the switch the terminal of the called-for station is projected into engagement with the connecting-shell. A constantly-operating alternating-current generator, to which the shell is normally connected, rings the called-for station. Immediately following this the terminal of the calling-sta-

tion is projected into engagement with the connecting-shell, the station is signaled, and the shell immediately drops to a point below 55 the line of circuit-terminals onto a heated insulated surface. A fusible section forming part of its structure is here gradually melted. The shell then releases the plug-terminals, and the take-up devices return said terminals 60 to normal position. The interval required for the release of the terminals is the period of time assigned to a conversation. The switch is operated by a "selecting" device composed of a series of longitudinally-movable notched bars. A series of switch-operating bars is located above the notched bars, crossing them at right angles. The notched bars are so constructed that by securing the proper arrangement a channel due to a series 70 of registering notches is formed under any predetermined cross-bar. The notched bars are moved by a traveling electromagnet, which moves back and forth across the ends of the bars, presenting the contact-point of 75 its armature-bar to each notched bar in succession. The travel of this magnet is synchronous with the movement of the tape-section through the transmitter, and the arrangement of the notched bars at the end of a transmitted call corresponds with the arrangement 80 of perforations in the tape-section. At the end of each excursion of this traveling magnet the connecting-shell is properly shifted, and the notched bars are returned to their normal position by means of an electromagnet. 85

The accompanying drawings illustrate my invention.

Figure 1 is a complete view of the invention. Fig. 2 shows one of the transmitting 90 tape-sections employed at the substation. Fig. 3 shows the switching device employed at the main station. Fig. 4 is a section of same on the line G H, Fig. 3. Fig. 5 shows one of the connecting-shells. Fig. 6 is a vertical cross-section of a connecting-shell. Fig. 7 is a top plan view of the switching device shown in Fig. 3. Fig. 8 is a detail view of the pivoted support for a circuit-terminal. Fig. 9 shows the circuit terminal or plug and its 100 support. Fig. 10 is a view of the selecting device on the line A B, Fig. 1. Fig. 11 is a view of the selecting device on the line E F, Fig. 10. Fig. 12 is a cross-section of the se-

lecting device on the line C D, Fig. 1; and Fig. 13 is a view of the supporting-bar of the selecting device when shifted.

The switching device.—The switching device at the main station is shown in Figs. 3 to 9, inclusive. There are a series of levers 40, pivoted at 41 in a circle, as shown in Fig. 7. Each lever has a short arm 42 and is connected by a link 43 with the armature-bar 44 of a magnet 45. The series of magnets 45 are supported on a circular base-board 46. Each subscriber's circuit comes direct to a screw-post *d* and to a flexible cord *c*, terminating in plug *p*. There is a conducting-contact 47 on the base of this plug. The free end of the arm 40 is ring-shaped, as shown at 48, Fig. 8, and a ring 49 is pivoted within the ring 48 on the points 50 and 51. The circuit passes through this contact 47 to arm 40 and to a common ground 110. The usual arrangement of gravity take-up 52, consisting of a flat lead weight and pulley running on the cord *c*, is provided for each cord. The rods 40 normally hang under the influence of the weights 52 in a vertical position. When the short end 42 of the rod 40 is depressed by the attraction of the armature-bar 44, on closing circuit through magnet 45 the terminal or plug *p* is carried upward to a common central point *e*, as shown by the dotted lines in Fig. 3.

There are a series of connecting-shells *a*, Figs. 5 and 6. Each such connector consists of a short cylindrical section 55 of metal, closely fitting a second similar section 56 of metal. There is a tube-section 58 forming part of the section 56. This occupies a central position with respect to cylinder 55. The entrance to tube-section 58 is slotted at 59. The section 55 closely fits the section 56. The section 56 is provided with an upper flange 57 and a lower flange 60. Each flange has a slot, the slot in one being diametrically opposite that in the other, as shown at 61 and 62. The exposed exterior of the connecting-shell *a* is preferably covered with a coating of heat-conducting insulating material, such as vitreous enamel. Within the cylinder 55 are two pairs of springs *s*. These springs are all electrically united, have a flaring opening, and conform to the outline of the terminal or plug *p*. When plug *p* enters a spring-contact *s*, it is caught and held. The springs *s* are constructed with a tendency to diverge or separate, but are held in operative position by plugs or sections of some easily-fusible material or some easily-fusible alloy *w*. The material *w* may be either beeswax, beeswax and resin, or what is called a "triple" alloy—such as bismuth, five parts; tin, two parts; lead, three parts; mercury, one part. This amalgamated alloy melts at from 165° to 170° Fahrenheit. The object of this fusible section is to provide for releasing the plugs by the influence of heat, as will be described. The connectors *a* or connecting-shells are made in two parts to facilitate the application of the fusible sections *w* after they have been displaced by use. The

connectors *a* are arranged upon a vertical rod *f*, provided with a rib 64, closely fitting the slot 59 in the connector *a*. A fixed projection or finger 65 supports the column of connecting-shells *a*. The rod *f* is in such a position that one of the pair of springs *s* of the connectors *a* normally rests at the common central point *e*, to which the terminals *p* are carried. When one terminal has been thrown into engagement with the connector at *e*, the connector is given a semirotation, thereby presenting the second pair of springs *s* at the central point *e*. When the second terminal has been connected, the connectors are given a second semirotation, which brings them into the position they first occupied. The finger 65 normally rides under the lower flange 60, and the slot in this flange 61 is at the opposite end of a diameter. When the shell receives its first semirotation, the slot 61 is carried into registering position with the finger 65, and the finger allows the column of shells to drop, catching upon the second flange 57. Upon the second semirotation of the shells the slot 62 in the flange 57 allows the finger 65 to pass through, and the shell *a*, supporting the combined weight of the two terminals *p*, with their pulley-weights, drops down, and its weight is such that its gravity exceeds the combined weight of the take-up devices 52. The connecting-shell rests after it drops upon the metal table 66, which is heated by a gas-burner 67 and has a coating of vitreous enamel 68 on its upper surface. This is to prevent crossing circuits when more than one connector rests upon the table. The heat of this table is established at such a degree that the fusible section *w* will melt and release the plug *p* from the spring *s* in the period of time established for the duration of a conversation—let us say five minutes. The gravity take-up devices 52 then return the plugs *p* to their normal position, thus separating the talking-circuit and establishing the individual circuits.

The means for imparting a semirotation to the vertical rod *f* consists of a weight 70, with a cord 71 wound upon a barrel 72, fixed to the shaft *f*. At a point below the barrel there is fixed on the shaft *f* an escapement 73, controlled by an armature-bar 74 and operated by an electromagnet 75 in circuit with the battery 76, and a circuit-closer controlled by the selecting device, to be described. The disk 73 has two teeth or projections, as shown, at diametrically opposite points. An electric impulse in the coil of magnet 75 withdraws the armature-bar 74, allowing notched disk 73 to make a half-rotation. An alternating-current generator *g* is connected to ground and to the rod *f*. This generator operates constantly. The connecting devices *a* while in position on the rod *f* are in connection with the generator *g*. When the called-for station-terminal *p* is projected into engagement with the spring *s* at the point *e*, the called-for-station bell is rung, and when the

calling-station terminal immediately following this is placed in contact with the connector the bells of both stations are rung till the connector is released from its normal position. Each of the bars 40 is operated by an armature-bar 44 and an electromagnet 45. Each magnet 45 is in a separate local circuit, and any one of these circuits is selected to be operated by a suitable selecting device.

10 *The selecting device.*—The selecting device is shown in Figs. 1, 10, 11, 12, and 13 at *h*. It includes a suitable framework *i* and two groups or series of metal bars or blades. One series, *n*, is arranged to slide lengthwise. The upper edge of each bar is slotted. I call them "slotted" bars *n*. Above the slotted bars *n*, at right angles and in close proximity, are a series of bars or blades *o*. These are thin metal blades pivoted on a rod at 80. I call them "fingers." Each constitutes the movable member of a circuit-closing device in circuit with wire 243, a battery 244, a magnet 45, and a fixed contact 81, Fig. 12. There is a bar *j* which normally supports the entire series of fingers *o*, leaving the slotted bars *n* free to move. The bar *j* is connected to a fixed bar 82 by means of two pivoted links 83 and 84. The link 83 has a retracting-spring 85. Link 84 has a retracting-spring 86. The springs pull in opposite directions and hold the links in a vertical position. When bar *j* is moved in either direction longitudinally, it is lowered or dropped. This allows fingers *o* to rest upon slotted bars *n*. By properly arranging the slots in bars *n* a channel is provided under some single finger *o*, whereby it is allowed to drop below the line of the other fingers. It then makes contact with said spring 81 and closes the circuit. I have shown seven bars *n*—a number sufficient to provide for one hundred and twenty-eight different circuits. Each notched bar *n* added to the series will double and add one to the number of possible combinations. Thus eight bars *n* will provide for two hundred and fifty-seven circuits. To cause any finger *o* to drop while all others are held, one or more of the bars *n* are moved longitudinally. To do this, I provide an electromagnet *k* on a carriage 90, traveling on a screw 91, rotated by a constantly-operating electric motor *x* in either direction. Motor-armature 92 is connected to screw 91 by a friction-clutch 93. There is a magnet *m* responsive to currents of one polarity only. There is a magnet *k* responsive to currents of the opposite polarity only. Both magnets are fixed upon the traveling nut or carriage 90. Armature-bar 95 of magnet *m* when carriage 90 is in its position of rest enters a slot in the disk 94, fixed on the screw 91, holding the traveling carriage, while the motor *x* continues to rotate. The friction-clutch 93 permits this action. There is a fixed bar 96 in the same vertical plane with screw 91. Upon this the carriage 90 travels. Magnets *m* and *k* are in the common ground-wire 110, which is connected to the pivoted supports 41 of the

series of arms 40, as shown in Fig. 1. There is a screw 111 arranged parallel with the notched bars *n*. A nut *q* travels upon this screw and upon the fixed parallel rod 114. The screws 91 and 111 are geared together by bevel gear-wheels 112 113. When a call-signal is transmitted from the substation, the first impulse is always, let us say, a negative impulse. This causes magnet *m* to withdraw armature-bar 95 from the slot in disk 94. The constantly-operating motor *x* immediately rotates the screw 91 and carriage 90 starts on its travel. As the magnet *k* presents its armature-bar 115 to the end of each of the notched bars *n* in succession, a current impulse when received causes armature-bar 115 to move a notched bar *n* a distance approximately one-half the distance between two adjacent fingers *o*. At the end of the travel of magnet *k* across the series of bars *n* notches in each bar have been so aligned that a channel is formed under one of the fingers *o*. Traveling nut *q* has moved at the same rate as magnet *k*, and when magnet *k* has passed the bars *n* nut *q* has engaged the "fast" and "loose" contact device 120. There are two pairs of these fast and loose devices fixed to the sliding bar *j*. The members of each pair operate in respectively opposite directions. When the devices 120 and 121 are operated by the nut *q*, said nut passes device 121 freely in moving from right to left, Fig. 1, but engages device 120 and moves bar *j*. In moving from left to right nut *q* passes device 120 freely and engages device 121, thus moving bar *j* in the reverse direction. Each so-called "fast" and "loose" device consists of a right-angled lever having a long arm and a short arm. Each device is pivoted at the angle, as 122. A spring 123 tends to hold each such device in its normal position. The nut *q* in moving from the position shown in Fig. 1 first encounters the projection 121, deflects it, and passes to the projecting arm 120. Its engagement with 120 causes sliding bar *j* to move longitudinally until it takes the position represented in Fig. 13, where the nut *q* is shown at the point of passing and releasing 120. When released, spring 85, connected to link 83, returns the bar *j* to its normal position. While bar *j* was below its normal plane, the fingers *o* dropped onto the edges of the bars *n*, and one of them dropped into an aligned channel.

140 and 141 are the movable and fixed parts of a circuit-closing device in circuit in conductor 142, with magnet 143, battery 76, and magnet 75. Circuit-closer 140 is operated by the fast and loose devices 130 and 131. When nut *q* moves the bar *j* from right to left, the device 130 rubs across the point 140 and is deflected; but on its return movement it is not deflected and operates to depress circuit-closer 140, closing the circuit 142. The armature of magnet 143, carrying the long bar 245, engages the ends of the bars *n* and returns these bars to their normal posi-

tion. Simultaneously the magnet 75 attracts its armature-bar 74. This releases the vertical rod *f*, which escapes one-half revolution, as above described. When the traveling carriage 90 reaches the limit of its movement, it engages the projection 150 of the motor-reversing device *v*. This device is composed of a sliding bar frictionally held. It has two terminal projections 150 and 151 and a central projection 107, which is connected to a battery 108 and to ground by conductor 109. 5 105 is a spring-contact connected by conductor 103 with motor-coil 101 and thence to earth. Spring-contact 106 is connected by conductor 104 to motor-coil 100 and thence to earth. When the circuit-reversing device *v* is shifted, battery 108 is connected in circuit with motor-coil 100 or 101, according to which 15 105 or 106 is in contact with the terminal 107. The armature 92 of motor *x* is permanently connected in circuit with battery 102. Coils 100 and 101 are so wound that battery 108 polarizes them oppositely. When traveling carriage 90 has engaged projection 20 150, circuit is closed through field-coil 101 of motor *x*. The motor rotates in a direction to cause the carriage 90 to travel toward it. When traveling carriage 90 strikes projection 151, circuit through coil 101 is broken 25 and immediately established through coil 100. The motor now rotates in the opposite direction, producing reversed movement of carriage 90. The carriage 90 normally rests in the position shown. When started into 30 operation, it advances, arranging the bars *n* as it moves. It then shifts the bar *j*, which bar on its return movement restores the normal position of the bars *n* and shifts the connecting device. The carriage 90 now 35 starts on its return, again arranging the bars *n* to represent the calling-station. The nut *q*, moving with it, passes the device 120, but engages the device 121, while the device 131 now operates the circuit-closer 140, 40 as in the instance first described. When the carriage 90 strikes the projection 151, the motor is reversed, and the armature-bar 95 of magnet *m* drops into the slot in the disk 94, stopping further movement. 45

50 *The automatic transmitter.*—To obviate the demand for skill and intelligence at the substation, an automatic transmitter *t* is provided. This is composed of a rotating drum 20, contact-fingers 21 and 22, and grounded batteries of opposite polarity 23 and 24, respectively connected to the contact-fingers 21 and 22. The drum has a central row of feed-teeth 25 and is propelled by a coil-spring 26, wound by a crank 27, like a district telegraph 55 signal-box. An escapement 28 is employed to render the operation uniform and gradual. There is a slideway 29, through which the section of tape *b* is introduced to pass between the contact-fingers and the drum. The transmitting tape-section *b* is shown in detail in Fig. 2. It is provided with seven feed-holes to the inch arranged in a central line 30.

The current-transmitting perforations are arranged along the edges. The single perforation 35 in the division 31 is designed to transmit an impulse of, say, negative polarity to release and start the controlling-magnet of the selecting device. The division 31 is designed to afford an opportunity for the transmitter to take hold of the strip and to allow 70 the traveling controlling-magnet to start before the current impulses which control the arrangement of the longitudinal bars are transmitted. These current impulses are of, say, positive polarity and are due to the perforations in the division of tape 32. While the two short divisions 33 are passing, the traveling magnet reaches the end of its excursion and starts back. The perforations in the division 34, arranged in reverse order as 75 compared with those in division 32, determine the second arrangement of the longitudinal bars. It is to be understood that the relative position of the perforate and imperforate areas in a unit length of the tape, as in tape- 80 division 32, arbitrarily represents the arrangement of notched bars in the selecting device which operate the terminals of the called-for station and that the arrangement of the spaces in the tape-division 34 similarly 85 represents the arrangement of the notched bars corresponding to the calling-station. These tape divisions and sections are all of uniform size and extent. The signal of the calling-station occupies the space 34 on all 90 tape-sections, and there is one tape-division 32 perforated for each of the other exchange circuits or stations. It is designed that these tape-sections shall be provided and distributed by the proprietors or managers of the 95 exchange. The designation by name or number of the called-for station is printed upon the tape-section. The drawing Fig. 2 shows the actual size of the tape-section.

The method of operation.—At each substation there is the usual arrangement of gravity-switch, battery-transmitter, and hand-telephone. There is a condenser in the bell branch, and an alternating-current generator may also be supplied. I have shown a hand-switch *u* with means for connecting the substation-circuit 200 with the telephone set through the conductor 201 or with the automatic transmitter in the conductor 202. Either ground-return or metallic circuits may 110 be employed. I have shown ground-return circuits for illustration. If it is desired to use metallic circuits, the circuit-terminals must be provided with double contacts and the two pairs of spring-contacts in the shell-connectors must be properly divided to produce the corresponding electrical connections. 115

The operation of the apparatus is as follows: A subscriber lifts his hand-telephone 120 and listens. If the line is quiet and free from what he understands to be current impulses from another call-transmitter, he replaces the telephone, turns the handle 27 of trans-

mitter *t*, and simultaneously inserts the tape-section *b*. The first impulse is from the battery 24, circuit passing through contact-finger 22, perforation 35, wheel 25, line 202, 5 switch *u*, line 200, connecting-post *d*, cord *c*, plug *p*, lever 40, pivotal circular support 41 to common ground 110, and is effective in magnet *m*, which withdraws its armature-bar from the slot in disk 94. This frees the 10 screw 91, and carriage 90 begins to move. When armature-bar 115 reaches a point in line with the first of the slotted bars *n*, the first feed-hole in section 32 of the tape-section *b* is in line with the contact-point 21. 15 When armature-bar 115 is in line with the second slotted bar of the series *n*, the second feed-hole and the first perforation appearing in division 32 of tape-section *b* is in line with contact-finger 21. A positive impulse from 20 battery 23 passes over line 202, thence via elements *u*, 200, *d*, *c*, *p*, 40, 41 to 110, as just described, and is effective in magnet *k*. The second slotted bar is thus longitudinally displaced a distance approximately one-half the 25 space between the fingers *o*. At the transmitter *t* tape-section *b* moves synchronously with the advance of the armature-bar 115, and at the end of the travel of carriage 90 bars *n* have been displaced in conformity 30 with the perforations in division 32 of tape-section *b*. Carriage 90 continues its movement. The nut *q*, propelled by screw 111, operating through the device 120, shifts bar *j*. A finger of the series *o* drops, closing circuit 35 through spring 81, conductor 243, battery 244, and magnet 45. An arm 40 is thrown up, projecting the terminal *p* at the point *e* into double spring-contact *s* in the shell-connector *a*. Bar *j* is returned by its spring. Circuit is closed at 140 and 141 via conductor 40 142, magnet 143, battery 76, and magnet 75. The vertical rod *f* rotates one-half turn. This presents the second pair of springs *s* at the point *e* and allows the finger 65 to pass 45 through the slot 61 in the flange 60. Magnet 143 simultaneously attracts its armature, and bar 245 returns the series of bars *n* to their normal position. At the end of its travel carriage 90 engages the projection 150, throwing the point 107 into engagement with the point 105. The motor-coil 101 is now in a circuit 103 105 107 108 109 to the ground return. The nut *q* and the carriage 90 immediately begin their return movement. The 50 tape-section *b* has now reached the point indicated by the dotted line in the division 33. The operation of arranging the slotted bars *n* in conformity with the perforations in division 34 of the tape-section *b* is repeated. Then 55 traveling nut *q* engages the device 121, shifting bar *j* in the opposite direction, which results in the same drop. Spring 86 then returns the bar *j*, and the device 131 operates the circuit-closer 140, as above described. 60 The carriage 90 continues its movement and engages the projection 151. Circuit is broken through coil 101 of the motor and made

through coil 100. The motor starts to reverse; but screw 91 is caught and held by the armature-bar 95, which drops into the slot in the disk 94, and the apparatus assumes its normal position of rest ready for another call. Immediately following the described connection of the circuit-terminals and the release of the connector *a* from the vertical shaft *f* 75 the connector *a* drops onto the table 66, which is heated by the gas-burner 67. Connector *a* will naturally assume the position shown in dotted line in Fig. 1, the heat being maintained at such a point that the terminal-plugs 80 are allowed to escape by the melting of the fusible sections and the spreading of the spring-contacts *s*, each cord and plug assuming its normal position under the influence of the take-up devices 52 ready for the next call. 85

What I claim, and desire to secure by Letters Patent, is—

1. The combination in a telephone - exchange of a series of independent, movable circuit-terminals, a series of independently- 90 movable, portable connecting devices and means for automatically uniting pairs of circuit-terminals with a connecting device, at a common point, successively.

2. The combination in a telephone - exchange of a series of independent, movable circuit-terminals, a series of independently- 95 movable, portable connecting devices, having receptacles for said circuit-terminals, and means for automatically uniting pairs of circuit-terminals with a connecting device, at one common point, successively.

3. The combination in a telephone - exchange of a series of independent, movable circuit-terminals and a series of independently- 100 movable, portable connecting devices having receptacles for said circuit-terminals; means for automatically uniting pairs of said circuit-terminals with a connecting device, at one common point, successively, and means 110 for automatically disconnecting said terminals and connecting device.

4. The combination in a telephone - exchange of a series of circuit-terminals, means for moving said terminals in separate and independent paths to one common point, successively, a series of portable connecting devices, and means for presenting said connecting devices, successively, at said common point to receive pairs of circuit-terminals. 115

5. The combination in a telephone - exchange of a series of independent circuit-terminals, means for moving said terminals in separate and independent paths to one common point successively, a series of portable 125 connecting devices, with means for moving said devices, successively, to said common point to receive the circuit-terminals and for displacing said connected terminals and connecting device.

6. The combination in a telephone - exchange of a series of movable circuit-terminals, means for moving said terminals in separate and independent paths to one common

point, successively, a series of connecting devices having sockets to receive said terminals, means for presenting said devices at said common point, successively, means for displacing said connected terminals and connecting device and means for automatically releasing said terminals and returning them to normal positions.

7. The combination in a telephone - exchange of a series of main and sub station circuits, an automatic call-transmitter at a substation, a selecting device at the main station operated by said transmitter; means for automatically connecting circuits in pairs controlled by said device and means for disconnecting said circuits by the influence of heat.

8. The combination in a telephone - exchange of a series of main and sub station circuits, an automatic call-transmitter at a substation, a selecting device at the main station operated by said transmitter, means for automatically connecting circuits in pairs controlled by said device and means for disconnecting said circuits including a heated support and a source of artificial heat.

9. The combination in a telephone - exchange of a series of main and sub station circuits, a switching device at the main station for connecting said circuits in pairs and means for disconnecting said circuits by the gradual application of heat to the connecting device.

10. The combination in a telephone - exchange of main and sub station circuits, an automatic call-transmitter at a substation; a selecting device at the main station consisting of (a) a series of movable parts or elements, one for each circuit, (b) a series of controlling parts or elements, in number a fractional part of the first-named series, (c) means for arranging said second series of elements operated by said transmitter, movable circuit terminals, one for each circuit, and suitable operating connections between said terminals and the first-named elements, respectively.

11. The combination in a telephone - exchange of main and sub station circuits, an automatic call-transmitter at a substation; a selecting device at the main station consisting of (a) a series of movable parts or elements, one for each circuit, (b) a series of controlling parts or elements, in number a fractional part of the first-named series, (c) means for arranging said second series of elements operated by said transmitter, movable circuit terminals one for each circuit and operating connections between said terminals and the first-named elements, respectively, each such connection including a local circuit, an electromagnet and a circuit-closer.

12. The combination in a telephone - exchange of main and sub station circuits, a suitable call-transmitter at a substation, an automatic switching device at the main station, a selecting device including two series of movable elemental parts, one series controlling said switching device, the second series controlling the first, and a moving electro-

magnet presenting its armature-bar to operate each elemental part in said second series in succession.

13. The combination in a telephone - exchange of main and sub station circuits, a suitable call-transmitter at a substation, an automatic switching device at the main station, a selecting device including a plurality of movable elemental parts arranged in operative relation in two series, one series controlling the switch, the other series controlling that first named, a moving electromagnet presenting its armature-bar to each elemental part in the second series in succession, and means whereby said magnet arranges said elemental parts according to the plan or pattern determined by transmitted impulses.

14. The combination in a telephone - exchange of main and sub station circuits, an automatic call-transmitter at the substation including a perforated strip or medium, an automatic switching device at the main station, a selecting device including two series of movable elemental parts arranged in operative relation, one series controlling said switching device, the second series controlling that first named, a moving electromagnet presenting its armature-bar to each elemental part in the second series in succession and means whereby said magnet operates to arrange said elemental parts in accordance with the perforations and spaces in said perforated strip.

15. The combination in a telephone - exchange of main and sub station circuits, an automatic switching device at the main station operating to connect circuits in pairs, means for controlling said switching device at the main station including an electromagnet, an automatic call-transmitter at the substation with a series of separate, perforated controlling strips or sections, one for each of a series of substations, each section being characteristically marked or perforated to transmit a predetermined succession of current impulses whereby said electromagnet is actuated to control the connection of the circuits corresponding to the section selected or employed.

16. The combination in a telephone - exchange of main and sub station circuits, an automatic call-transmitter at the substation including a portable strip or medium having one or more unit-spaces, each space characteristically divided into perforated and unperforated areas arranged in line, an automatic switching device with a selecting device at the main station, the latter consisting of two series of bars, strips or elements, each series movable in planes at right angles and an electromagnet device in circuit with said transmitter; said device operating to arrange one series of elements in two divisions corresponding to the perforated and unperforated spaces in said portable strip or medium.

17. The combination in a telephone - exchange of a series of main and sub station cir-

cuits, a suitable call-transmitter at a substation, automatic switching apparatus at the main station including a suitable selecting device, a series of circuit-terminals, a series 5 of rods or supports in which said terminals are separably located, respectively, means whereby said rods or supports are each movable in a separate, distinct, and independent plane to project said terminals at a common 10 point, and means whereby said call-transmitter automatically controls said switch.

18. The combination in a telephone-exchange of a series of main and sub station circuits, a suitable call-transmitter at a substation, automatic switching apparatus at the main station including a suitable selecting device, a series of circuit-terminals and a series of rods or supports, on which said terminals are separably supported, respectively, 15 means whereby said rods or supports are each free to move in a separate, distinct and independent plane to project said circuit-terminals at a common point and a suitable connecting device separably supported at said point.

25 19. The combination in a telephone-exchange of a series of main and sub station circuits, a suitable call-transmitter at a substation, automatic switching apparatus at the main station including a suitable selecting device, a series of circuit-terminals, a flexible cord for each terminal, a retracting device for each cord, a series of rods or supports on which said terminals are separably supported, respectively, means for moving each 30 rod or support in a separate, distinct, and independent plane into engagement with a connecting device located at a point common to all said terminals, a suitable connecting device, and means for displacing said connecting device when the talking-circuit is formed.

20. The combination in a telephone-exchange of a series of main and sub station circuits, a suitable call-transmitter at a substation, automatic switching apparatus at the main station including a series of circuit-terminals, a series of rods or supports on which said terminals are separately supported, respectively, means for moving each rod or support in a separate plane to project said terminals at a common point, and a suitable detachable connecting device located at the common point.

25 21. The combination in a telephone-exchange of a series of main and sub station circuits, a suitable call-transmitter at a substation, automatic switching apparatus at the main station including a series of circuit-terminals, a series of rods or supports, one for each circuit-terminal, means for moving each 50 rod or support in a separate plane to carry its terminal to a common point, a detachable connecting device at said common point and means for shifting the position of said connecting device to receive the second circuit-terminal.

22. The combination in a telephone-exchange of a series of main and substation cir-

cuits, a suitable call-transmitter at a substation, automatic switching apparatus at the main station including a series of circuit-terminals, a series of rods or supports, one for each circuit-terminal, means for moving each terminal in a separate plane to a common point, a detachable connecting device at said common point, and means for shifting the 75 position of said connecting device and for disconnecting said circuit-terminals.

23. The combination in a telephone-exchange of a switching apparatus including a connecting device for connecting circuits in 80 pairs and means for fusing the connecting device.

24. The combination in a telephone-exchange of a series of substation circuit-terminals, means for automatically projecting 85 and connecting said terminals in pairs at a common point, a series of detachable connectors therefor and means for automatically disconnecting said terminals.

25. The combination in a telephone-exchange of a switching apparatus including independently-movable circuit-terminals, means for presenting said terminals at a common point, a series of portable connectors having sockets, means for presenting said connectors successively at said common point, a selecting device and means for operating said device to connect circuits in pairs.

26. The combination in a telephone-exchange of a switching apparatus, including a 100 series of detachable connectors and means for advancing said connectors singly and successively; with a selecting device consisting of a plurality of movable, elemental parts, arranged in two series; means whereby one of 105 said series controls the other; means whereby the controlled series operates the switching apparatus, and a suitable moving or traveling device to control one series of elements of the selecting device.

27. The combination in a telephone-exchange of a selecting device consisting of a plurality of movable blades or bars arranged at an angle to each other in separate planes, a traveling magnet to control one of said series of bars, a circuit for said magnet and a suitable transmitter in said circuit.

28. The combination in a telephone-exchange of a series of longitudinally-movable bars; a series of pivoted bars in a plane parallel thereto, a traveling magnet movable into position to divide said longitudinal bars in two groups, a suitable transmitter and a circuit including said magnet and transmitter.

29. The combination in a telephone-exchange of a series of independent, movable circuit-terminals, a series of movable connecting devices having sockets or terminal-receptacles; means for selecting terminals to be connected, consisting of two series of movable elements, one series controlling the circuit-terminals, respectively, the second series collectively controlling the first; an automatic transmitter at a substation having a

series of portable circuit-controlling devices each divided into two unit-spaces arranged to throw upon the line current impulses representing the calling and the called-for circuits, and means whereby a circuit-controlling device controls the selecting device.

30. The combination in a telephone-exchange of a series of circuits, a suitable call-transmitter at a substation, a selecting device at the main station, means for controlling said selecting device operated by said transmitter, a switching device for uniting circuits in pairs, consisting of a series of movable circuit-terminals and portable connectors having sockets or receptacles, and means for including said connectors in circuit, successively, to unite pairs of circuit-terminals.

31. The combination in a telephone-exchange of a series of circuits, a suitable call-transmitter at a substation, a selecting device at the main station, means for controlling said selecting device operated by said transmitter; a switching device for uniting circuits in pairs, consisting of a series of movable circuit-terminals and detachable connecting devices having terminal-receptacles, means for including said connecting devices in circuit, successively, to unite pairs of circuit-terminals and means for automatically disconnecting said circuit-terminals.

WILLIAM BALDWIN VANSIZE.
